UNITED STATES PATENT OFFICE

2,422,803

AUTOMATIC SLOTTING MACHINE

Emil A. Schigut, Van Nuys, Calif.

Application September 17, 1943, Serial No. 502,741

15 Claims. (Cl. 164—87)

1

My invention relates to an automatic slotting machine and more particularly to a machine for automatically making bayonet and other slots in fastener elements.

An object of the invention is to provide work feeding means and cutting means that are relatively movable one with respect to the other, to produce substantially spiral grooves, recesses or slots in fastener elements.

Still another object of the invention is to provide means for rotating work and by means of the rotation thereof to effect forward feeding of same, whereby to substantially spirally feed the work with respect to a cutting means.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of a multiple machine embodying the foregoing objects.

Fig. 2 is a side elevation, partly broken away, of said embodiment.

Fig. 3 is a horizontal plan view principally of clutch mechanism comprised in the embodiment.

Fig. 4 is a vertical section taken on the line 4—4 of Fig. 3.

Fig. 5 is a diagrammatic view of connections comprised in the invention.

Fig. 6 is an enlarged, broken, sectional view of a feeding chuck comprised in said embodiment.

Fig. 7 is a horizontal, sectional view of the mechanism shown in Fig. 6.

Fig. 8 is a face view of a product of the present machine, with cutting means arranged diagrammatically opposite same.

Fig. 9 is a face view taken substantially at right angles to Fig. 8.

Fig. 10 is an end view of said product of the present machine.

Fig. 11 is a broken, diagrammatic view of a valve comprised in the embodiment, in a different operative position.

2

Referring more in detail to the drawings, the reference number 12 generally designates a table by which the present machine is supported. Legs 13 are arranged to support the table member. A rigid metal plate 14 is supported on the table, upon which the operating mechanism of the present machine is mainly mounted.

A motor 15 is arranged between the legs of the table for driving the present machine. The motor 15 operates continuously and the power is taken therefrom as needed. It is to be understood that the machine shown in the drawings is a multiple machine having four distinct operating mechanisms. To drive these four mechanisms, twin shafts 16 and 17 are driven by the motor 15 through the intermediary of belts 18 and 19 and sheaves 20 and 21 on the shafts 16 and 17 respectively. The shaft 16 is mounted in bearings 22, 23 and 24 in the frame of the machine, while shaft 17 is mounted in bearings 25, 26 and 27 mounted in parallel relation with the first mentioned bearings. The bearings 24 and 27 are arranged upon a bracket frame 28 extending horizontally and laterally from the main table support, as perhaps best shown in Fig. 3.

Suitable clutch means 29 and 30 are arranged to connect the shafts 16 and 17 respectively to crown clutch members 31 and 32 on the sheaves 20 and 21 respectively. Levers 33 and 34 are pivotally mounted on arms 35 and 36 on the bracket frame 28. The levers 33 and 34 are operated by suitable pedals (not shown), through the intermediary of connecting rods 37 and 38, respectively.

The pump 39 is mounted on the frame under the top 12. A three-way, manual valve 40, a fluid motor 41 and a reservoir 42 are arranged in series in a fluid circuit, with the pump 39. A cam 43 on the shaft 17 engages a roller 44 on piston rod 45 of a piston 46 in the pump 39.

A piston 47 in the fluid motor 41 drives piston rod 48 to which is connected a rack 49, by means of a crosshead 50. Pinion 51 is driven by the rack 49. A return spring 52 acts upon the rack 49 to return the rack 49 and piston 47 to the left in Fig. 5, when fluid pressure in the fluid motor 41 permits same.

The fluid circuit on the power stroke is as follows: Reservoir 42, conduit 53, pump 39, conduit 54, three-way valve 40, conduit 55, fluid motor 41. When the piston 47 uncovers the port 56 leading to a bleeding line 57, then the flow is through the conduit 57 back into the reservoir

42, without further motion being imparted to the piston 47.

The fluid circuit on the return stroke is as follows: To effect a return stroke, the three-way valve 40 is manually turned to the position shown in Fig. 11. Then the flow is from the fluid motor 41 through conduit 55 through three-way valve 40, through conduit 58, through conduit 57 to the reservoir 42 and through conduit 53 to the pump 39. Fluid movement through conduit 54 is prevented when the valve 40 is in the position shown in Fig. 11. A check valve 59 prevents retrograde movement of liquid back into the pump 39 from conduit 54, while check valve 60 prevents retrograde movement of liquid from the pump 39 back into the conduit 53.

Mounted within the pinion 51 is a chuck 61 provided with a bayonet arranged groove 62. A collet 63 (split longitudinally along the bottom, as shown in Fig. 6, to make it resilient) is arranged concentrically within the chuck 61. A sleeve 64 is interposed between the chuck body and the collet 63. A work centering tool 65 is mounted within the collet 63. The end of the tool 65 has a screw driver head 66 that engages a slot 166 in a flange 67 of the work.

The inner end of the collet 63 has a threaded connection with a rod 68 that is slidable in a screw cap 69 on the rear end of the sleeve 64. A coiled spring 70, interposed between an abutment 71 on the rod 68 and the cap 69, tensions the grip of the collet 63 upon the flange 67 of the work, by means of the engaging, tapering shoulders of the collet 63 and the sleeve 64. The outer, rear end of the rod 68 has a handle 72 pivotally connected thereto, at 110. The handle 72 has a cam 73. In the full line position of the handle 72, in Fig. 6, the cam 73 moves the abutment 71 toward the cap 69, thus drawing the collet 63 tight around the flange 67 of the work. To release the work, the handle 72 is moved to the broken line position, thereby moving the cam 73 away from the abutment 71, permitting the rod 68 to move to the right, in Fig. 6, thereby releasing the pressure of the collet 63 upon the work.

A housing 74 supports a guide 75 for the rack 49 and rotatably supports the sleeve 64, chuck 61, collet 63, tool 65, the work, the pinion 51, the rod 68 and cap 69, the handle 72 and the spring 70. Suitable ball bearings 16 are provided for this rotary support. This entire assembly, within and upon the housing 74 is slidable to the right and left, in Fig. 6. A depending guide 77 under the housing 74 slidably engages a guide groove 78. A rearward stop 79 is provided for the housing 74. A plate 41a is secured between each pair of housings 74 on which motor 41 is mounted, whereby the housings and the motor are slidable forwardly and backwardly as seen in Fig. 1.

Fixed bearings 80 are provided opposite each other, substantially at right angles to each work holder. Bushings 81 are provided in the bearings 80 for reciprocating bars 82. Cutting tools 85 are also provided. They may be any suitable cutting means. Reciprocating punches 83 are shown as suitable examples. They are provided with heads 84, which heads are held between threaded connections 85 of the reciprocating bars 82 and caps 86. In other words, the rods are inserted through the central bores in the caps 86 with the beveled heads 84 of the punches resting against similarly shaped shoulders within the caps 86. Then the caps 86 are screwed upon the

projecting, threaded bosses 85 on the reciprocating bars 82.

One of each pair of bearings 80 contains a stationary guide pin 87, which engages with the bayonet slot 62. By this means the chuck 61 is fed forward as it is rotated, whereby the chuck travels spirally.

The reciprocating bars 82 have pins 88 engaging inclined slots 89, 90 and 91 in vertically reciprocating arms 92, 93 and 94. Stationary guides 95 and 96 aid in directing vertical movement of the arms 92 and 94. Eccentrics 97 have connecting rods 98 that are pivotally connected with the reciprocating arms 92, 93 and 94 by means of pivot pins 99. The eccentrics 97 are driven by cams 100 on the shafts 16 and 17. Reciprocation of the arms 92, 93 and 94 causes the punches or cutting tools 83 to reciprocate with respect to the work 101. The arms are timed so that the punches or cutting tools strike the work simultaneously at diametrically opposite points. This action aids in maintaining the work in its centered position.

Knobs 102 are provided on the ends of the racks 49, to provide manual means for retracting the racks in case the machine stops with the punches in the work. It is also to be understood that hand-wheels (not shown) may be provided on the shafts 17 to rotate them in case they stop at dead center.

Central plates 112 on the plate 14 separate the work space into two parts. Between the plates 112 is a space 113 for waste material.

In the operation of the device, the blank work 101 is arranged manually in the chuck 61 with the flange 67 of the work within the resilient grip of the collet 63 and with the head 66 engaging the slot 166 of the work. The handle 72 is then moved from the unlocked, broken line position to the full line position of Fig. 6, thus locking the work in place. The housing 74 is thereupon moved forward manually until the pin 87 engages the slot 62. The foot pedal (not shown) is then actuated to connect the rotating motors with the shafts 16 and 17.

The cams 100 on the shafts cause reciprocation of the eccentrics 97 and in turn reciprocate the arms 92, 93 and 94, which in turn reciprocate the bars 82, thereby causing reciprocating operation of the punches or cutting tools 83. As the work 101 is rotated by the fluid circuit shown in Fig. 5, the pin 87 and slot or groove 62 effects a forward, spiral movement to the chuck and work. The work was previously bored endwise at 103.

Disengaging the clutch means permits the spring 52 to return the fluid motor 41 to its original position, which retracts the chuck 61 and the work 101. The finished product is then released by moving the handle 72 from the full line position to the broken line position of Fig. 6. The finished product is then removed by hand.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a machine of the character described, a work feeding chuck having a master bayonet groove therein, said chuck having a grooved col-

let for the flange of a blank, a relatively fixed guide engaging the groove, motor actuated driving means connected to rotate the chuck continuously, the engaging guide and slot being arranged to feed the chuck forward, following the contour of the master groove, when the chuck is rotated by the driving means, and a percussion tool disposed to punch the work continuously as the chuck is rotatively fed forward uninterruptedly generally in a spiral path, punching into the blank a slot following the contour of the master groove.

2. In a machine of the character described, a work feeding chuck having a master groove therein, a relatively fixed guide engaging the groove, a pinion connected to rotate the chuck about the axis of the chuck, a rack connected to drive the pinion, a fluid motor operatively connected with the rack, a closed fluid circuit for the motor, fluid pump means in the circuit means to drive the fluid pump, supplying pressure fluid to the motor, means to automatically relieve the fluid motor when it has reached its maximum driving position, the engaging guide and slot being arranged to feed the chuck forward following the contour of the master groove when the chuck is rotated by the driving means, and a cutting tool disposed to cut into the work as the chuck is rotatively fed forward generally in a spiral path, cutting into the blank in a path following the contour of the master groove.

3. In a machine of the character described, a framework, a chuck mounted for rotary movement upon the framework and arranged to slide simultaneously with respect thereto, reciprocable fluid pressure actuated driving means connected to rotate the chuck and being slidable therewith, releasable means on the chuck disposed to grip a flange of work material, the chuck and a relatively stationary part of the framework having an engaging groove and pin arranged to effect forward sliding movement of the chuck by its rotary movement, and cutting means arranged to remove material from the work in a pattern following said groove.

4. In a machine for slotting hollow work material, percussion punch means disposed to reciprocate along a fixed longitudinal axis, rotary work holding means mounted to have a reciprocating motion, reciprocable fluid pressure actuated means to rotate the work holder and being slidable therewith, the work holder and a relatively stationary part of the machine having a substantially spiral groove and pin means engaging each other, the pin and groove being inclined to feed the work holder forward by rotation thereof, and means to reciprocate the percussion punch means to and fro along said axis, the punch means punching a slot in the work material following the pattern of the spiral groove and continuously as the work material is moved forward.

5. In a machine for slotting hollow work material, oppositely disposed percussion punching means mounted to reciprocate longitudinally toward and away from each other, driving means for continuously reciprocating the punching means to cause same to slot the work material, rotary work holding means mounted to have a reciprocating motion, means to rotate the work holder, the work holder and a relatively stationary part of the machine having engaging inclined groove and pin means, the incline of the groove being arranged to feed the work holder

forward between the opposite punching means and during the punching operation.

6. In a machine for slotting hollow work material, oppositely disposed percussion punching means mounted to operate longitudinally toward and away from the work material, driving means connected continuously to operate the punching means to slot the material, and means to feed work continuously between and simultaneously with the oppositely operating cutting means, to slot the work simultaneously from opposite sides continuously during the feeding of the work and to maintain the work centered between the cutting means.

15 7. In a machine for slotting hollow work material, diametrically oppositely disposed punches mounted to reciprocate longitudinally toward and away from each other, driving means connected to reciprocate the punches toward and away from each other substantially simultaneously, rotary work holding means having resilient gripping means for the work, the work holding means being mounted to reciprocate and connected to feed the work to a centered position between the oppositely operating punches, the resilient mounting releasably holding the work, means to rotate the work holder, the work holder and a relatively stationary part of the machine having a substantially spiral groove and pin means engaging each other, the pin and groove being inclined to feed the work holder forward by rotation thereof.

20 8. In a machine for slotting hollow work material, a frame, a chuck assembly reciprocably mounted on said frame, a plurality of work holding chucks rotatably mounted on said assembly, said chucks each having a pinion to effect rotation thereof, a rack member adapted to actuate said pinions, a fluid motor on said assembly adapted to actuate said rack, flexible power supply means connected to said motor and said frame and having control means independent of said assembly, a plurality of punch means disposed to reciprocate along a longitudinal axis in mutual spaced relation, whereby to punch a pair of elongated slots in diametrical portions of the work when said assembly is reciprocated to advance the work between said punch means.

25 9. In a machine for slotting hollow work material, a frame, a chuck assembly reciprocably mounted on said frame, a plurality of work holding chucks rotatably mounted on said assembly, said chucks each having a pinion to effect rotation thereof, a rack member adapted to actuate said pinions, a fluid motor on said assembly adapted to actuate said rack, flexible power supply means connected to said motor and said frame and having control means independent of said assembly, a plurality of punch means disposed to reciprocate along a longitudinal axis in mutual spaced relation, whereby to punch a pair of elongated slots in diametrical portions of the work when said assembly is reciprocated to advance the work between said punch means, and means to actuate said punch means.

30 10. In a machine for slotting hollow work material, a frame, a chuck assembly reciprocably mounted on said frame, a plurality of work holding chucks rotatably mounted on said assembly, said chucks each having a pinion to effect rotation thereof, a rack member adapted to actuate said pinions, a fluid motor on said assembly adapted to actuate said rack, flexible power supply means connected to said motor and said frame and having control means independent of said assembly, a plurality of punch means dis-

posed to reciprocate along a longitudinal axis in mutual spaced relation, whereby to punch a pair of elongated slots in diametrical portions of the work; when said assembly is reciprocated to advance the work between said punch means, and means to actuate said punch means, last means comprising bar members reciprocable at right angles to said punch means, and having angular slotted engagement therewith, a rotary power shaft for said bar members, and eccentric crank means connected between said shaft and said bar members.

11. In a machine for slotting hollow work material, percussion punching tools mounted to reciprocate longitudinally toward and away from opposite sides of the work material, means continuously to reciprocate said punching tool continuously to remove part of the work material to form slots therein, and means to advance the work material continuously in a spiral path during the continuous reciprocation of said punching tool.

12. In a machine for slotting hollow work material, percussion punching tools mounted to reciprocate substantially at right angles to the longitudinal axis and on opposite sides of said work material, means continuously to reciprocate said punching tool continuously to remove part of the work material to form slots therein, and means to feed the work material continuously forward during the slot punching operation.

13. In a machine for slotting hollow work material, a work holder, percussion tools mounted to reciprocate substantially at right angles to the longitudinal axis and on opposite sides of said work material, means to reciprocate said tools continuously to remove part of the material from the work to form slots therein, yielding means continuously to rotate said work holder and slideable therewith, and means to feed the work material forward continuously during the continuous operation of the punching tool.

14. In a machine of the character referred to,

work holding means, percussion tools for removing part of the work material from opposite sides thereof to form slots therein, and reciprocable transversely of the work, mechanism for yieldingly feeding the work holding means forwardly and spirally in a predetermined orbit and simultaneously with the operation of said percussion tools to cause the tools to punch the work fed by said holding means.

15. In a machine of the character referred to, work holding means for a cylindrical work blank, yielding driving means to rotate said holding means, means controlled by the rotation of said holding means to feed the blank holding means continuously forward spirally, and percussion means reciprocable transversely and simultaneously at diametrically opposite points of the work to maintain the work centered and punch the blank continuously spirally to form slots therein as the blank is continuously fed forward.
